INVENTOR

Franklin R. White

BY George L. Smith
ATTORNEY

UNITED STATES PATENT OFFICE.

FRANKLIN R. WHITE, OF WATERBURY, CONNECTICUT, ASSIGNOR TO THE PATENT BUTTON COMPANY, OF WATERBURY, CONNECTICUT, A CORPORATION OF CONNECTICUT.

FASTENER.

SPECIFICATION forming part of Letters Patent No. 692,953, dated February 11, 1902.

Application filed May 2, 1901. Renewed January 10, 1902. Serial No. 89,224. (No model.)

To all whom it may concern:

Be it known that I, FRANKLIN R. WHITE, a citizen of the United States, and a resident of Waterbury, in the county of New Haven and 5 State of Connecticut, have made and invented certain new and useful Improvements in Fasteners, of which the following is a specification.

My invention relates to an improvement in 10 fasteners, and more particularly to the socket member of a ball-and-socket fastener, such as are generally used upon gloves, umbrella-bands, clothing, &c., the object of the same being to provide an article of this kind or 15 character which shall be simple and cheap to manufacture, easily and readily applied to the fabric or material, and effective in retaining the ball member therein and preventing it from accidental disengagement.

With these and other ends in view my invention consists in certain novel features of construction and combinations of parts, as will be hereinafter fully described and then pointed out in the claims.

In the accompanying drawings, Figure 1 is a sectional view showing the two parts of the socket member prior to their attachment to the material. Fig. 2 is a similar view showing the parts after attachment. Fig. 3 is a 30 plan view of the eyelet member. Fig. 4 is a sectional view of a modified form of the article prior to its attachment, and Fig. 5 a similar view thereof after attachment to the material. Figs. 6, 7, and 8 show modified forms 35 of the outer shell.

As will be seen by reference to the drawings, my improved socket consists of two parts, A representing the outer shell and B the fastening-eyelet, said shell A being preferably 40 concavo-convex in form, the edge a thereof being curled or bent upwardly and inwardly to form a lock or anchor for the fastening-eyelet. The eyelet B consists, preferably, of a shank b and a base or flange c , the top d of 45 the eyelet, which may be either an open or closed one, being bent downwardly and inwardly within the shank b and preferably slotted or slotted at the bend, as shown at e . In securing this socket member in place the 50 shell A and eyelet B are placed on opposite

sides of the material and the eyelet B by means of proper tools forced within the shell A, carrying the cloth or material C with it. As the depressed top d of the eyelet is forced upwardly the shank b of the eyelet is forced 55 outwardly—that is, the shank is spread until the top d thereof conforms to the shape of the domed top of the shell A, the upper portion of the shank being spread over the curled rim a of the shell, as shown in section in Fig. 60 2, thereby holding the material between the shell and eyelet and securely locking these two members together. By slitting or slotting the upper portion of the fastening-eyelet, as described, the shank of the eyelet is 65 permitted to spread evenly, although it will be understood that such slots are not absolutely essential.

Instead of depressing the top of the eyelet, as described, said eyelet may be formed of 70 the usual shape—that is, as illustrated in Fig. 4, b' representing the shank of the eyelet, c the flange, and d the top. Within this shank b' is inserted a cup-shaped disk h , of such diameter as to be nicely contained 75 within said shank. When the parts are assembled, as before described, pressure is exerted upon said disk h , which tends to straighten or flatten, the effect being that the top of the eyelet is spread, as in the first instance, over and upon the curled rim of the shell, as illustrated in Fig. 5, securely locking 80 the parts together, the cloth or material being held between the eyelet and shell, as before described. In either instance it will 85 be noticed that the locking together of the eyelet and shell is effected by spreading or expanding the upper end of the eyelet over and upon the curled rim of the shell and to such an extent that no ordinary strain will 90 separate them. Again, instead of forming the outer shell as described it may be shaped as illustrated in Fig. 6—that is, with a flat top A' , converging sides, and a straight or flattened flange or case a' , or, as illustrated in 95 Fig. 7, the top A^2 may be flat and the lower edge a^2 curled to form the seat or anchor, and, again, it may be shaped as illustrated in Fig. 8, wherein the top A^3 is dome-shaped and curved inwardly and having a base or flange 100

a³. In all these instances—that is, when shaped as shown in Figs. 1, 6, 7, and 8—it will be noticed that said shell has a restricted opening whereby to prevent the disengagement of the fastening-eyelet after being spread therein.

Having fully described my invention, what I claim as new, and desire to secure by Letters Patent, is—

10 1. The socket member of a ball-and-socket fastener, consisting of an outer shell having a restricted opening and a fastening-eyelet, the top of which is closed and depressed or recurved, whereby said top may be expanded and locked within said shell, substantially as described.

15 2. The socket member of a ball-and-socket fastener, consisting of a shell having a restricted opening, and a fastening-eyelet, said eyelet comprising a shank or tubular portion,

the top of which is closed, depressed and slit, and at its opposite end a flange, whereby the closed, depressed top of said eyelet may be expanded and locked within said shell, substantially as described.

25 3. The socket member of a ball-and-socket fastener, consisting of a shell having a curled rim, and an eyelet, consisting of a flange and shank, the top of said shank being closed and depressed or recurved, whereby the same may be spread or expanded over and upon said curled rim, substantially as described.

Signed at Waterbury, in the county of New Haven and State of Connecticut, this 26th day of April, A. D. 1901.

FRANKLIN R. WHITE.
